UNITED STATES PATENT OFFICE

LOUIS MAURICE BERNON, OF LONDON, ENGLAND, ASSIGNOR OF ONE-HALF TO ROBERT JAMES WALKER, OF LEICESTER, ENGLAND

APPARATUS FOR AUTOMATICALLY CONTROLLING THE FEED WATER OF STEAM BOILERS

Application filed March 17, 1927, Serial No. 176,160, and in Great Britain April 13, 1926.

This invention relates to apparatus for automatically controlling the flow of fluids under pressure, such as boiler feed-water, and has for its essential feature a valve for this purpose coupled to an operating element wherein the power for moving the latter (and thus indirectly to actuate the valve) is derived from the pressure of the incoming fluid. The control of this operating element is under the influence of the level in the vessel being fed.

In the present invention the controlling element is a double-headed piston between and past the heads of which the incoming fluid can flow, the piston moving to operate the valve according as a pair of openings in its cylinder vary in area, the variation being dependent upon the condition of the vessel being fed.

In more particular terms defining an embodiment, the said invention comprises a main fluid valve operating in conjunction with a piston in a chamber always in communication with the pressure fluid on the inlet side of the said fluid valve. Said piston is double-headed and unpacked so as to be a free fit in the chamber and the fluid pressure acts between the heads to set up normally a balance and condition of rest, this condition being varied as and when the area of opening at a pair of outlets to the piston chamber (one at the other side of each piston head) becomes unequal and leakage past the piston heads unbalanced, the piston then moving to actuate the main fluid valve through suitable linkage. Means are employed, influenced by the level in the boiler or the like, to control automatically the said areas of opening, and thus indirectly to govern the movement of the main fluid valve.

The invention will be better understood by reference to the following description of embodiments more in detail which are illustrated by the accompanying drawings, wherein:—

Figure 1 shows, in vertical section, a main fluid valve with its actuating means, coupled up to a control chamber influenced by boiler liquid level.

Figure 2 is a vertical section of a modified form of control chamber.

Referring to the drawings, the apparatus comprises a valve-controlled, vertically or otherwise disposed, chamber 1 which is connected up to a pump which forces water into said chamber under pressure greater than the steam pressure of the boiler. For this member, which is the main fluid valve, a double-
55 beat valve 2 is shown.

This water chamber 1 is formed with a horizontal branch pipe 3 carrying a vertically disposed cylinder 4 in which is slidably mounted a plunger which is constituted by two opposite opposed unpacked pistons 5, of equal area, carried by a rod 6 common to both pistons. Said rod 6 is connected to the one end of a pivotally mounted lever 7 located in the branch pipe aforesaid, the other end of said lever being connected to the vertically disposed spindle 8 of the valve 2 aforesaid, which valve controls the flow of feed-water from said chamber 1 to the boiler. The direction of flow is indicated by arrows.

Arranged exteriorly of the boiler is a vertically disposed vessel 9, which may be termed a control chamber, the upper part of which constitutes a steam chamber, and the lower part a well to which water from the boiler is supplied by way of an opening 10, whilst the steam chamber is connected by pipe to the steam space of the boiler, through opening 11, so that the level of the water in the well corresponds with the level of the water in the boiler.

In the well aforesaid there is provided a bucket or other float 12 which (as in Figure 1) is connected to the horizontally disposed arm 13 of a counterbalanced or weighted (preferably adjustably) bell-crank lever 14 which is pivotally mounted above said bucket or other float 12, whilst to the vertically disposed arm of said bell-crank lever there is pivotally connected the one end of a link 15 which, by its other end, is pivotally connected to the lower end of the long arm 16 of a lever with unequal arms, the other arm being designated 17.

The upper end of the short arm 17, which is pivotally mounted in the upper part of the

steam chamber aforesaid, is operably connected to a horizontally disposed spindle which, at each end thereof, is fitted with a valve 18 and 19 adapted to open or close correspondingly disposed ports in the head of the control chamber 9.

Further, the one port controlled by valve 18 is, by a pipe 20, connected to the space 21 above the upper piston 5 of the plunger, whilst the other port controlled by valve 19 is, by a pipe 22, connected to the space 23 below the lower piston 5 of said plunger.

Assuming the water in the well to be at high water level, and that the valve 18 controlling the port connected with the space 21 above the upper piston 5 is fully open, and the valve 19 of the port connected to the space 23 below the lower piston 5 of the plunger is closed (not necessarily tightly on its seating), then the pressure on the outsides respectively of the pistons 5 (due to leakage past the pistons of the incoming fluid) will become unbalanced; the resistance in chamber 21 becomes eased and consequently the plunger assumes its upstroke position, shutting main valve 2.

On the water level in the boiler falling, and consequently the level of the water in the well 9 aforesaid, the bucket or other float 12 sinks and causes the bell-crank lever 14 to turn on its pivot, and through the link 15 connecting said bell-crank lever to the unequal arm lever 16 aforesaid to rock said lever on its fulcrum.

This results in the valve 18 closing more or less, whilst, at the same time, the valve 19 is fully opened, with the result that the unequal areas of opening to the chambers 21 and 23 are reversed and consequently the pressure of the water on the pistons 5, 5 aforesaid causes the plunger to move down. In practice it has been ascertained that if the openings to the chambers 21 and 23 are of equal area, then a condition of balance and rest is set up by the pressure between the heads 5, but if the areas of exit or opening are varied, then the pressure from the chamber 1 will move the plunger 5, 5 towards the openings of larger area as the pressure leakage past the piston at that side has greater freedom of escape.

This downward movement of the plunger 5, 5 through the intermediary of the lever 7 connected to said plunger and to the spindle 8 of the valve 2 of the water chamber 1, lifts said valve 2 from off its seat, thereby allowing water to flow from said chamber into the boiler under the action of the pump aforesaid.

As the water in the boiler rises to high level again, so does the bucket or other float 12 rise correspondingly, and through the bell-crank lever and unequal arm lever aforesaid operates the valves 18, 19 of the chamber in reverse manner, thus gradually closing the fully opened port and fully opening the closed port.

This results in that the plunger 5, 5 moves upwardly again, because the pressure of the incoming fluid past plunger 5 into the upper piston chamber 21 is eased by leaking back past its control valve 18 to the steam chamber aforesaid, and this upward movement of the plunger through the lever connected thereto and to the spindle of the water valve, closes down said valve 2 accordingly, thereby gradually reducing the flow of water therethrough to the boiler till such time as the water level in the boiler is restored to normal and the water valve closed down, cutting off the water supply to the boiler, and so on.

It will be followed that at all times the water pressure from pump is the same on the inner faces of each of the upper and lower pistons, and the movement of the plunger, which takes place, is due solely to the varying restriction of the one port 18 in relation to the other port 19, unbalancing the pressures of the respective leakages past the heads 5, 5, in the chambers 21 and 23.

Any suitable mode of varying the area of the openings to the chambers 21 and 23 under the influence of the boiler liquid level can be employed. By way of example, a modified form of control chamber 9, with its steam and water inlets 11 and 10, and float 12 is illustrated in Figure 2. In this form, the cranked arm 24 is fixedly attached to the mouth of the bucket 12. The central rod 25 is a fixture, and the bucket in rising and falling rocks about the pivot 26 by the connecting link 27.

By this device the bucket is guided and held firmly in vertical position, whilst oscillation thereof is obviated.

The bucket's movement rocks a counterbalanced arm 28 about a pivot 29, and so controls the valves 181 and 191. The latter are connected to the chambers 21 and 23 and operate as in the previously described example. The said valves 181 and 191 are capable of adjustment to and from their seatings by means of the adjustment devices 182 and 192 respectively.

Referring back to the cylinder 4 and its pistons 5, 5, it is pointed out that means may be employed to lock the plunger in its low position (main valve 2 open) if desired. For instance, a screw-down spindle device 30 will serve this purpose.

I claim:—

1. An apparatus for automatically controlling the flow of liquids under pressure, including a valve, an operating element coupled to said valve, and wherein the power for moving the operating element is supplied from pressure of the incoming fluid, comprising a double-headed piston constituting the operating element, between and past the heads of which the incoming fluid must flow, the piston moving to operate the valve according to the flow of liquid through the 120

openings in its cylinder, the variations depending upon the condition of the vessel being fed.

2. In apparatus for automatically controlling the flow of fluid under pressure to a vessel, a main fluid valve operated by an unpacked freely fitting double-headed piston reciprocating in a cylinder, a passage from the cylinder to the inlet side of the valve, said 10 passage communicating between the two piston heads, openings in the cylinder ends, and means automatically controllable by the fluid level in the vessel to regulate the flow of liquid through said openings and thus control 15 movement of the piston by the incoming fluid pressure, which leaks past the heads thereof, substantially as described.

3. Apparatus for automatically controlling the supply of boiler feed water comprising in combination a control chamber with a pair of valve-controlled openings, steam and water inlets to said chamber whereby a float rises and falls with the boiler water level, means whereby the float operates the valve-controlled openings, a main fluid valve governing the supply of boiler feed water, and a double-headed piston capable of operating the main valve, said piston reciprocating in a cylinder having an opening at each end 25 communicating respectively with the aforesaid two valve-controlled openings of the control chamber, substantially as described.

4. In apparatus for automatically controlling the flow of fluids under pressure to a vessel, a main fluid valve and coupled operating element including a double-headed piston reciprocating in a cylinder, a passage from the cylinder to the inlet side of the valve, said passage communicating between the two piston heads, openings in the cylinder ends, and means (automatically controllable by the level of liquid in the vessel) to regulate the flow of liquid through said openings and thus control movement of the piston by the incoming fluid pressure.

5. In an apparatus including a boiler and means for automatically controlling the flow of fluid under pressure thereto, a main fluid valve operating in conjunction with a piston 50 in a chamber always in communication with the pressure fluid on the inlet side of the said fluid valve, the piston in said chamber being double-headed and the fluid pressure acting between said heads to set up normally a balance and condition of rest, this condition being varied as the flow of liquid through a pair of outlets to the piston chamber (one at the outside of each piston head) becomes unequal, the double-headed piston then moving 55 to actuate the main fluid valve through suitable linkage, and means influenced by the level of liquid in the boiler automatically controlling said areas of opening.

6. Apparatus for automatically controlling the supply of boiler feed-water, comprising

ing in combination a control chamber with a pair of valve-controlled openings, steam and water inlets to said chamber whereby a float rises and falls with the boiler water level, means whereby the float operates the valve-controlled openings, a main fluid valve governing supply of boiler feed-water, a double-headed piston capable of moving under pressure of the feed-water introduced between the piston heads, said piston operating in a cylinder having an opening at each end communicating respectively with the two valve-controlled openings of the control chamber, and connection means whereby the movement of the said piston opens and closes the main fluid valve, substantially as described.

In testimony whereof I have affixed my signature hereto this 31st day of January, 1927.
